Primary Examiner — Jasmine Mlinarcik*(74) Attorney, Agent, or Firm* — The Dobrusin Law Firm, P.C.; Bryan S. Lemanski(57) **CLAIM**

The ornamental design for a rain bonnet, as shown and described.

DESCRIPTION

FIG. 1 is a perspective view of a rain bonnet showing my new invention.

FIG. 2 is a front elevational view thereof.

FIG. 3 is a rear elevational view thereof.

FIG. 4 is a top view thereof.

FIG. 5 is a bottom view thereof.

FIG. 6 is a left side view thereof; and,

FIG. 7 is a right side view thereof.

The broken lines depict features, as well as depict portions of the rain bonnet that form no part of the claimed design.
